(57) CLAIM

The ornamental design for a combination hand mirror and comb as shown and described.

DESCRIPTION

FIG. 1 is a perspective view of a combination hand mirror and comb showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is another perspective view thereof;

FIG. 10 is another perspective view thereof;

FIG. 11 is a front view thereof;

FIG. 12 is a back view thereof;

FIG. 13 is a left view thereof;

FIG. 14 is a right view thereof;

FIG. 15 is a top plan view thereof;

FIG. 16 is a bottom plan view thereof; and,

FIG. 17 is another perspective view of a combination hand mirror and comb showing my new design, in which the comb is shown inserted through a side slot of the mirror. The broken lines depict portions of the combination hand mirror and comb and form no part of the claimed design. The hand mirror and the comb are shown separately for clarity of illustration.
